UNITED STATES PATENT OFFICE

LEWIS EDWIN MITCHELL, OF COLUMBUS, OHIO, ASSIGNOR TO THE JEFFREY MANUFACTURING COMPANY, OF COLUMBUS, OHIO, A CORPORATION OF OHIO

ROPE-WINDING DEVICE

Application filed November 1, 1928, Serial No. 316,537. Renewed August 5, 1930.

The present invention relates to certain new and useful improvements in rope winding devices, and particularly to devices adapted to wind the feed rope of coal cutting mechanism of the class adapted to rest upon and slide in any direction over the mine floor, and to control the unwinding of said rope.

The especial object of this invention is to provide improved actuating and controlling mechanism for the feeding devices of a mining machine of the class described, which shall be convenient of operation and reliable and durable in service.

The means whereby I attain these, and other objects, will be fully set forth in the following specification and illustrated in the accompanying drawings of which

Fig. 1 is a plan view of a mining machine equipped with the devices of my invention.

Fig. 2 is a side elevation of the machine illustrated in Fig. 1.

Fig. 3 is a fragmentary plan view, on an enlarged scale, of the feeding and guiding mechanism, certain parts being broken away to reveal parts lying below.

Fig. 4 is a vertical sectional view taken along the line IV—IV of Fig. 3.

Fig. 5 is a vertical sectional view taken along the line V—V of Fig. 3.

Fig. 6 is a fragmentary sectional view taken along the line VI—VI of Fig. 3.

Figs. 7, 8 and 9 are diagrammatic figures illustrating the operation of the machine.

Like numerals refer to similar parts in the several figures.

In the drawings the numeral 1 refers to the main supporting frame which is adapted to rest upon and slide in any direction over the mine floor. The numeral 2 indicates the rigid horizontally projecting cutter arm in the edges of which are formed guideways wherein travels the cutter chain 3. The cutter chain 3 is provided with cutter bits 4 adapted to engage the coal to cut it. The

cutter chain 3 passes around and is actuated by a sprocket wheel 5. The sprocket wheel 5 is mounted concentric with and operatively connected to a bevel gear wheel 6 which is engaged by a bevel pinion 7 mounted upon

these devices are well understood in the mining machine art and need no further description at this time. The motor 8 may be of any preferred type suitable to the condition under which the machine operates. For purposes of illustration I have here shown an electric motor with which is associated a controller 9 having an operating handle 10 convenient to the hand of the operator. Attached to the motor 8 is a socket 11 adapted to receive the attachment plug fixed to the end of a flexible conductor cable whereby connection may be established with a convenient source of electric current supply. As such devices are well understood in the mining machine art further illustration and description is not thought to be required at this time.

The feeding and guiding mechanism comprises two winding drums 12 and 13 upon which are windable the feed ropes 14 and 15 adapted to cooperate with suitable abutments external of the machine. The drums 12 and 13 are mounted for free rotation concentric with the vertical shafts 16 and 17 which are symmetrically positioned at either side of the longitudinal center line of the machine in a plane extending perpendicular thereto. These shafts are journaled in bearings formed in the hubs 18 and 19 of the main frame. Fixed to the shafts 16 and 17 are the worm gear wheels 20 and 21 both of which engage the worm 22. The worm 22 is formed integral with the worm shaft 23 which is journaled in roller bearings 24 and 25 suitably supported by the main frame of the machine. The worm shaft 23 is connected with the driving shaft of the motor 8 by a pair of spur gears 26 and 27. The arrangement being such as to permit the motor to occupy the lowest possible position thereby reducing the height of the machine and adapting it to use in extremely thin veins of coal.

Since the actuating mechanism of the drums 12 and 13 are alike a description of one will apply to both. To the upper flange 28 of the drum 12 is fixed an upstanding annular flange 29 having inwardly projecting gear teeth which engage two spur pinions 30. The pinions 30 are freely journaled on the

spindles 31 fixed to the spoke of the wheel 32 which is journaled upon the vertical shaft 16. The pinions 30 also engage a gear wheel 33 which is fixed to the shaft 16. Other pinions 34 are fixed to the pinions 30 concentric therewith, and these engage the inwardly projecting gear teeth formed on a ring 35 which is supported by the flange 29 but is freely rotatable relative thereto. Brake bands 36 and 37 are arranged to engage the peripheries of the ring 35 and wheel 32 associated with drum 12 to resist their rotation about the axis of the shaft 16 under the control of mechanism to be hereinafter fully described. The arrangement and proportions of these parts is such that when the ring 35 is held against rotation the drum 12 will revolve in a rope winding direction at relatively low speed, and when the wheel 34 is held against rotation the drum 12 will revolve in the rope winding direction at relatively high speed. When neither the ring 35 nor the wheel 34 is held against rotation the drum 12 will remain idle. It is apparent that a partial tightening of the brake bands 36 or 37 will permit more or less slippage between said brake band and its cooperating member thereby resulting in variations of speed proportionate to the amount of slippage. Brake bands 38 and 39 are similarly arranged to control the ring 35 and wheel 32 associated with drum 13.

Attached to each of the brake bands 36, 37, 38 and 39, is a lug 40 which projects between the lugs 41 of the main frame to anchor the brake band against rotary movement about the axis of its cooperating member. A pivot pin 42 extending through suitable apertures in the lugs 40 and 41 helps to support the weight of the brake bands. Similar, but oppositely disposed lugs 43, 44, 43' and 44', are attached to the brake bands 36 and 37 at their ends, and these lugs are pierced by apertures through which project the control shafts 45 and 46, respectively. These control shafts are journaled in suitable bearings of the main frame and cooperate with the pivot pins 42 to prevent vertical displacement of the brake bands. Positioned between the lugs 43 and 44, 43' and 44', and encircling their respective control shafts, are compression springs 48 which bear against abutments 49 of the main frame and tend to expand the brake bands to prevent their engagement with their respective cooperating members. Fixed to the shaft 45 is a thrust collar 50 which engages the lug 43', and a polygonal nut 51 screw-threaded to the shaft 45 and fitting in a corresponding recess in lug 44' is adapted to be drawn, by rotation of said shaft, into contact with the lug 44' to compress the brake band 37 and cause its engagement with the wheel 32. A similar thrust collar 52 and screw nut 53 is provided upon the shaft 46 to control the

brake band 36 and the shafts 45 and 46 are connected together by gears 54 and 55 in such manner that rotation of said shafts will cause equal and opposite movement of the nuts 51 and 53 causing engagement of one brake band 70 and release of the other. To the shaft 46 is fixed a spur gear 56 which engages a similar gear 57 formed integral with the sleeve 57 journaled in a bearing formed in the bracket 58 of the main frame. To this sleeve is attached a hand wheel 59 positioned convenient to the hand of the operator. When the hand wheel 59 is rotated in one direction the drum 12 will be caused to revolve in a rope winding direction at a relatively high 80 speed, and when said hand wheel is rotated in the opposite direction the winding drum 12 will be caused to revolve in a rope winding direction at a relatively low speed. When said hand wheel stands in its central or neutral position, the winding drum 12 will remain idle, and a partial movement of said hand wheel will cause a slipping engagement of one or the other of the brake bands 36 or 37 whereby rotation of the winding drum 12 in 90 the unwinding direction may be resisted.

Projecting through the sleeve 57 is a shaft 60 having at one end a hand wheel 61 and at the other end a pinion 62 which engages a gear wheel 63 fixed to a control shaft 47. 95 The shaft 47 projects through the lugs 64 and 65 of the brake band 39, and is provided with a thrust collar 66 and screw nut 67 for the control of said brake band. A sleeve 68 rotatable upon the shaft 46 extends 100 through the lugs 69 and 70 of the brake band 38, and this sleeve is provided with a thrust collar 71 and screw nut 72. The sleeve 68 is connected with the shaft 47 by a spur gear 73 meshing with the gear 63. Manipulation 105 of the hand wheel 61 will cause rotation of the control shaft 47 and sleeve 68 thereby controlling the rotation of the winding drum 13 in the manner above described.

By the arrangement of parts above described the feed drums 12 and 13 may be controlled to wind their respective ropes either simultaneously or separately at a relatively fast speed or at a relatively low speed, or the rotation of said drums in the unwinding 115 direction may be frictionally resisted.

It will be noted that the peripheral flange of the planet carrier 32 seats down over the upper margin of ring 35. Preferably the upper portion of ring 35 is of reduced diameter 120 so that the outer flange of wheel 32 may be given substantially the same diameter as the lower portion of the ring. It will be obvious that this arrangement makes for greater compactness and thus enables the height of the machine to be kept down.

In the operation of the machine either of the ropes may be used to move the machine at relatively high speed over the mine floor to position the machine relative to the ma- 130

terial which is to be cut. Both ropes may be drawn out from their respective drums and attached to suitable anchor jacks 74 positioned adjacent the coal face, and the hand wheels 59 and 61 manipulated to wind both ropes at relatively low speed to form the sumping or entering cut as shown in Fig. 7.

The machine may be fed from right to left by passing the feed rope 15 around the guide pulley 75 which is fixed to the forward end of the machine frame and thence to an anchor jack 76 at the left hand rib. The rope 14 may be drawn out from its drum and attached to an anchor jack 77 at the right hand rib. When thus arranged the hand wheel 61 may be manipulated to wind the rope 15 at a relatively low or cutting speed, and the hand wheel 59 manipulated to permit the unwinding of the rope 14 against frictional resistance, thereby maintaining the desired angular relation of the kerf cutter 2 to the face of the coal as the machine travels across said face as shown in Fig. 8.

The machine may be fed from left to right by passing the rope 14 around the guide pulley 78, and thence to an anchor jack 79 at the right hand rib. The rope 15 will then be drawn out from its winding drum and attached to an anchor jack 80 at the left hand rib. When thus arranged the hand wheel 59 may be manipulated to wind the rope 14 at a relatively low or cutting speed, and the hand wheel 61 manipulated to permit the unwinding of the rope 15 against frictional resistance thereby maintaining the desired angular relation of the kerf cutter 2 to the coal face as the machine travels across the face, as shown in Fig. 9.

What I claim is:

1. In a machine of the class described, the combination with a frame, of a winding drum mounted thereon, a planetary gearing system arranged to connect said drum with a source of rotative power, said planetary system including two cylindrical brake elements and brake bands cooperating therewith, terminal lugs at both ends of said brake bands, a shaft extending through apertures in the terminal lugs of each brake band, nuts screw threaded to said shafts adapted to engage said terminal lugs, and gears connecting said shafts for rotation in opposite directions, as and for the purpose set forth.

2. In a machine of the class described, the combination with a frame, of a winding drum mounted thereon, planetary gearing arranged to connect said drum with a source of rotative power, said planetary system including two cylindrical brake elements and brake bands cooperating therewith, terminal lugs at both ends of each brake band, a shaft extending through apertures in the terminal lug of each brake band, nuts screw threaded to said shafts adapted to engage said terminal lugs, and means to simultaneously rotate said shafts in

opposite directions, as and for the purpose set forth.

3. In a machine of the class described, the combination with a frame, of a winding drum mounted thereon, a planetary gearing system arranged to connect said drum with a source of rotative power, said planetary system including two cylindrical brake elements and brake bands cooperating therewith, terminal lugs at both ends of each brake band, a shaft extending through apertures in the terminal lugs of each brake band, a nut screw threaded to each of said shafts adapted to engage said terminal lug, gears connecting said shafts for rotation in opposite directions, and means to rotate said shafts, as and for the purpose set forth.

4. In a machine of the class described, the combination with a frame, of a winding drum mounted thereon, a system of power transmission devices arranged to connect said drum with a source of rotative power, said system including two cylindrical brake elements and brake bands cooperating therewith, each of said brake bands terminating in outwardly projecting lugs, a shaft extending through apertures in both lugs of each brake band, a shoulder on each shaft engaging one of said lugs, a nut screw threaded to each shaft adapted to engage the other lug of each brake band, and gears connecting said shaft to cause their rotation in opposite directions, as and for the purpose set forth.

5. In a machine of the class described, the combination with a frame, of a winding drum mounted thereon, a planetary gearing system arranged to connect said drum with a source of rotative power, said planetary system including two cylindrical brake elements and brake bands cooperating therewith, terminal lug on said brake bands, two shafts each extending through apertures in the terminal lugs of one of said brake bands, a collar on each shaft engaging one of said terminal lugs, a nut screw threaded to each shaft and each adapted to engage the opposite terminal lug, compression springs surrounding said shaft engaging said terminal lug and suitable abutments of the machine frame tending to expand said brake bands, gears connecting said shafts for rotation in opposite directions, and means to cause the rotation of said shafts in either direction to alternately compress one of said brake bands and permit the expansion of the other.

6. In a machine of the class described, the combination with a frame, of a winding drum mounted thereon, a plural speed transmission system arranged to connect said drum with a source of rotative power, control means for said transmission system including a pair of brake drums, a split brake band arranged to cooperate with each said brake drums, and means to alternately tighten one of said bands and release the other, said

means comprising a screw and nut device connecting the free ends of each of said bands, and connections between said devices whereby actuation of one of them in a tightening direction causes simultaneous actuation of the other in a releasing direction.

7. In a machine of the class described, the combination with a frame, of a winding drum mounted thereon, a plural speed transmission system arranged to connect said drum with a source of rotative power, control means for said transmission system including a pair of brake drums, a split brake band arranged to cooperate with each of said brake drums, and means to alternately tighten one of said bands and release the other, said means comprising screw and nut elements connecting the free ends of each of said bands, and a gear connection between said screw elements whereby actuation of one of them in a tightening direction causes simultaneous actuation of the other in a releasing direction.

8. In a machine of the class described, the combination with a frame, of a winding drum mounted thereon, a planetary gearing system arranged to connect said drum with a source of rotative power, control means for said transmission system including a pair of superposed coaxial brake drums, a split brake band arranged to cooperate with each of said brake drums, and means to alternately tighten one of said bands and release the other, said means comprising screw and nut elements connecting the free ends of each band, said screw elements being horizontally disposed and in parallel relation, and connections between said screw elements whereby actuation of one of them in a tightening direction effects simultaneous actuation of the other in a releasing direction.

9. In a machine of the class described, a vertical shaft, a drum rotatable about said shaft, means for driving the shaft, and planetary gearing for driving the drum from the shaft, said gearing including a ring concentric with the drum and rotatable relative thereto, and a further rotary element concentric with said drum and having a circular peripheral flange freely surrounding the upper portion of said ring.

10. In a machine of the class described, a vertical shaft, a drum rotatable about said shaft, means for driving the shaft, and planetary gearing for driving the drum from the shaft, said gearing including a ring concentric with the drum and rotatable relative thereto, said ring having a marginal section of reduced diameter provided on its inner surface with gear teeth, and a further rotary element concentric with said drum and having a circular peripheral flange freely surrounding the reduced portion of said ring.

11. In a machine of the class described, a vertical shaft, a drum rotatable about said

shaft, means for driving said shaft, and planetary gearing for driving the drum from the shaft, said gearing including a ring concentric with the drum and rotatable relative thereto, said ring having a marginal section of reduced diameter provided on its inner surface with gear teeth, and a planet gear carrier rotatable about the shaft and having a circular peripheral flange freely surrounding the reduced portion of said ring.

12. In a machine of the class described, a base plate, a vertical shaft supported on said plate, a drum rotatable about said shaft immediately above said plate, said drum being provided on its upper side with an upstanding peripheral ring having gear teeth formed on its inner surface, a second ring surrounding the first and rotatable relative thereto, the upper margin of said second ring projecting above the first and being provided on its inner surface with gear teeth, planet gears engaging the teeth of both of said rings, a drive gear on the shaft meshing with the planet gears, a carrier for the planet gears rotatable about the shaft and having a circular peripheral flange freely surrounding the upper margin of said second ring, and friction means arranged to cooperate with the outer faces of said second ring and said flange.

13. In a machine of the class described, a base plate, a vertical shaft supported on said plate, a drum rotatable about said shaft immediately above said plate, said drum being provided on its upper side with an upstanding peripheral ring having gear teeth formed on its inner surface, a second ring surrounding the first and rotatable relative thereto, said second ring having a portion of reduced diameter extending above the first ring and provided with gear teeth on its inner surface, planet gears engaging the teeth of both of said rings, a drive gear on the shaft and meshing with the planet gears, a carrier for the planet gears rotatable about the shaft and having a circular peripheral flange freely surrounding the reduced portion of said second ring, and friction means arranged to cooperate with the outer faces of said second ring and said flange.

In testimony whereof, I have hereunto set my hand:

LEWIS EDWIN MITCHELL.
